UNITED STATES PATENT OFFICE

WILLIAM C. KENNEY, OF CRANSTON, RHODE ISLAND, ASSIGNOR TO KENNEY MANUFACTURING COMPANY, OF CRANSTON, RHODE ISLAND, A CORPORATION OF RHODE ISLAND

DRAPERY ROD OR THE LIKE

Application filed April 15, 1931. Serial No. 530,231.

This invention relates to sectional curtain rods of the telescopic type in which a telescopic coupling member detachably connects the complementary rod sections whereby the rod is assembled as a self-contained unit which may be adjusted, within limits, for any desired width of opening to be curtained.

More particularly this invention relates to a rod assembly of this type wherein both the rod sections and the telescopic coupling member are of generally U-shaped cross section and each bears a repeated surface pattern.

With such a rod assembly, it is essential that the effect of continuous and unbroken alinement of pattern shall be preserved for the entire length of the rod, regardless of variations in cross-sectional depth of the several units, due to their telescopic engagement, for unless such alinement effect of the pattern is preserved, the appearance of the rod is spoiled. Obviously if the pattern, particularly where such pattern is a straight line pattern applied to the several units of the rod from end to end thereof, gives the impression of being uneven or out of line in different areas of the rod, the beauty of the rod is lost. It is of the utmost importance therefore that the effect shall not be one of interruption, with the pattern of one rod unit out of alinement with the pattern of the next rod unit which it is supposed to join and complete.

As illustrative of the principles involved, I show in the accompanying drawing a sectional telescopic rod of new structure and result.

In the drawing:—

Fig. 1 is a plan view illustrating an applied position of my new rod.

Fig. 2 is a fragmentary perspective showing my novel telescopic coupling member inserted into one of the rod sections.

Fig. 3 is a perspective view of said coupling member, removed.

Figs. 4 and 5 are cross sections on the lines 4—4 and 5—5, respectively, of Fig. 1.

Fig. 6 is an elevation, partly in longitudinal section, of the coupling member shown in Fig. 3, and particularly illustrating how

the effect of continuous unbroken pattern alinement is preserved even in areas of the coupling member of different cross sectional depth, and

Figs. 7 and 8 are cross sections on the lines 7—7 and 8—8, respectively, of Fig. 3 and illustrating such variations in cross-sectional depth.

I have indicated at A and B a pair of telescopic rod sections and at C a telescopic coupling member interposed therebetween and frictionally connecting the same.

All of said units preferably bear a repeated surface pattern, indicated at D, in Fig. 6, although in order to avoid needless duplication of pattern, I have shown in the drawing only the telescopic coupling member C of my rod assembly as bearing such pattern.

As contemplated herein, the members A, B and C are of generally U-shaped cross section, each presenting a top portion 1, preferably but not necessarily arched, and connecting a pair of spaced substantially vertical front and rear portions 2 which terminate in relatively short upturned inwardly extending flanges 3 spaced apart from each other as at 4, the free edges of which afford smooth and even rails or tracks for a traverse (not shown) if the rod is used for this purpose.

This combination of connecting top wall and spaced depending front and rear walls and inturned flanged edges at the lower ends of said side walls affords a rod construction of maximum strength and rigidity.

According to the present disclosure, the outer end of each rod section A and B is formed as an elbow adapted to be mounted by any suitable mounting upon supports E, which for the purposes of this application may be considered as being the side casings of a window or door. This showing, however, is purely illustrative since the outer ends of said rod sections may be straight, if desired, depending upon the particular use to which the rod is to be put.

The inner end of each rod section A and B is adapted for quick detachable engagement with the ends of the interposed coupling member C. Such engagement is a telescopic

frictional engagement, and as here shown, the inner end of section A telescopes into one end C¹ of coupling C and the opposite end C² of said coupling telescopes into the inner end of section B.

For this purpose, the end C² of said coupling C is of reduced, cross-sectional depth as compared with the end C¹ (see Figs. 3, 6 and 8).

- 10 In order to prevent such variation in cross sectional depth in different areas of the same unit C from destroying the alinement of the pattern D in said areas and thus producing a broken or staggered effect, I have deliberately avoided any crowding in of the metal at the point C³ where the cross sectional depths depart from uniformity.

The reduction in cross sectional depth of the area C² relative to the area C¹ is accomplished during the formation of the tube C by incorporating in such area C² an element for the take-up of surplus metal. Such element may conveniently be a channel bead 5 extending longitudinally of the top wall 1 of said member, and such bead functions both to absorb such surplus metal as well as to strengthen and stiffen the tube C in this area. In addition to providing such channel bead I also trim off a slight amount of the metal of the flanges 3 before the member C is drawn into tube form. This insures that the flanges 3 of the member C will be the same height as those of the members A and B.

35 The continuity of pattern D is thus preserved throughout the entire length of the member C (as clearly illustrated in Fig. 6). The fit of the member C within the rod section B is a close friction fit, due to the fact that the portion C² gradually tapers to the point C³. The fit of rod section A over said member C is a fairly easy fit so that section A may be readily telescoped onto and off member C without injuring the enamel or other attractive finish of the parts.

40 It will be understood that the inner ends of rod sections A and B are of the proper cross sectional depth to telescopically engage one another in the event that the member C is omitted.

45 Various modifications in the construction and design of my device, may obviously be resorted to if within the spirit and scope of my invention as defined by the appended claims.

50 What I therefore claim and desire to secure by Letters Patent is:

1. A sectional curtain rod, comprising a pair of end sections and an intermediate coupling member telescopically engageable with said end sections, said coupling member and both of said end sections bearing similar pattern fragments which when the several parts of the rod are assembled together form a complete pattern, said coupling member presenting adjacent its ends areas of vary-

ing cross-sectional depth, the area of greater depth fitting over one end section of the rod and the area of lesser depth fitting into the other end section of the rod, and the area of lesser depth being provided with a compensating formation adapted to take up the surplus metal resulting from said reduction in depth whereby the patterns carried by said coupling member and end sections are displayed in an effect of unbroken alinement continuously from end to end of the rod despite the variations in cross-sectional depth of the coupling member adjacent its end areas.

2. A sectional curtain rod as claimed in claim 1 wherein the compensating formation of the coupling member is a channel bead extending longitudinally of the area of reduced depth of said coupling member.

3. A sectional curtain rod as claimed in claim 1 wherein both the end sections of the rod and the coupling member are substantially U-shaped in cross section, and wherein the compensating formation of the coupling member is a channel bead extending longitudinally of the top wall portion of the area of reduced depth of said coupling member.

In testimony whereof I affix my signature.

WILLIAM C. KENNEY.
